[57] CLAIM

The ornamental design for a cylindrical shape handling bag and a combined beach towel, as shown and described herein.

DESCRIPTION

FIG. 1 is a front perspective view of a cylindrical shape handling bag and a combined beach towel being worn with a combined beach towel completely folded up into it showing my new design;

FIG. 2 is an enlarged perspective view thereof;

FIG. 3 is a front view thereof;

FIG. 4 is a top plan view thereof;

FIG. 5 is a bottom plan view thereof; and,

FIG. 6 is a right side view thereof, the left side being a mirror image. The broken line showing of experimental structure in FIG. 1 is for illustrative purposes only and forms no part of the claimed design.

The broken lines in FIGS. 2 to 6 represent stitching.
The strap is shown broken away in FIGS. 3-6 for ease of illustration.
